CLAIM

The ornamental design for a chandelier, as shown and described.

DESCRIPTION

FIG. 1 is a left side elevational view of chandelier showing my design;

FIG. 2 is a front elevational view thereof; the rear elevational view being a mirror image; and,

FIG. 3 is a top plan view, thereof.

The broken-line showing of environmental structures in FIGS. 1-3 is for illustrative purposes only and forms no part of the claimed design.
